UNITED STATES PATENT OFFICE.

JOHN MARSHALL, OF PAWTUCKET, RHODE ISLAND, ASSIGNOR OF THREE-FOURTHS TO ISAAC H. RUSSELL, OF FALL RIVER, MASSACHUSETTS, ABEL T. ATHERTON, OF BAYSIDE, RHODE ISLAND, AND CHARLES T. ATHERTON, OF PAWTUCKET, RHODE ISLAND.

MACHINE FOR TWISTING AND SPINNING FIBROUS MATERIALS.

SPECIFICATION forming part of Letters Patent No. 699,203, dated May 6, 1902.

Application filed May 6, 1901. Serial No. 58,867. (No model.)

To all whom it may concern:

Be it known that I, JOHN MARSHALL, a citizen of the United States, residing at Pawtucket, in the county of Providence, State of Rhode Island, have invented a certain new and useful Improvement in Machines for Twisting and Spinning Fibrous Materials, of which the following is a specification, reference being had therein to the accompanying drawings.

The invention has relation to twisting and spinning frames of the class in which rotating rings are employed in lieu of the fliers formerly used.

15 The invention consists in a novel means of supporting a rotating ring in machines such as referred to and in the means of effecting lubrication.

The invention involves the use in connection with a rotating ring of antifriction-rolls or the like for the purposes of affording lateral support to the ring, and preferably vertical support as well, and in addition restraining the ring from rising out of place.

25 In the drawings, Figure 1 shows in vertical transverse section on the plane indicated by the dotted line 1 1, Fig. 3, a ring-rail having applied thereto a rotating ring of the character hereinbefore mentioned and illustrates one

30 embodiment of the invention. Fig. 2 is a view in vertical transverse section on the plane indicated by the dotted line 2 2 in Fig. 3. Fig. 3 shows in plan a portion of the length of the said rail and some of the parts which are applied thereto in practice. Fig. 4 shows in

35 plan a pair of the antifriction rolls or wheels and their carrying-plate removed from the rail. Figs. 5 to 9 are partly-sectional detail views showing modifications.

40 Having reference to the drawings, the ring-rail is designated 1, and the rotating ring is designated 2. In the present instance it is contemplated that the ring 2 shall be driven by means of a band applied to the same, and

45 the groove for the reception of the said band is designated 2^a.

In Figs. 1 to 3 I have illustrated an embodiment of the invention in which ring 2 has employed in connection therewith four

antifriction rolls or wheels 3 3, &c., mounted 50 in connection with the ring-rail and arranged symmetrically around the ring 2. These rolls or wheels constitute lateral bearings which sustain the ring against tendency to movement transversely. The rolls or wheels are 55 shown mounted on vertical axes. Herein the rolls or wheels revolve upon pins 3^a 3^a, carried by plates 3^b 3^b, resting on lugs 1^a 1^a, that are cast or otherwise provided on the rail 1, the said plates being secured in place by 60 means of screws 3^c 3^c, passing through transverse slots 3^d 3^d in the said plates into tapped holes in the said lugs 1^a 1^a. Suitable heads or collars 3^e 3^e on the lower ends of the pins 3^a 3^a afford vertical support to the rolls or 65 wheels 3 3. In this embodiment of the invention the peripheries of the rolls or wheels 3 3 are formed with V-shaped grooves receiving a projecting V-shaped rib 2^b, with which the ring 2 is formed or provided. By the entrance of the V-shaped rib into the V-shaped grooves the ring 2 is supported vertically and at the same time is held from rising. Obviously the construction just described may 70 be reversed by forming the ring with a V-shaped groove and forming the rolls or wheels 2 2 with V-shaped peripheries to enter the groove in the ring. 75

A rotatable ring mounted and supported in the manner which I have just described is 80 capable of working at exceedingly high velocities and with very slight friction and wear. The matter of properly lubricating the bearing-surfaces is of exceedingly great importance in connection with spinning appliances, 85 and especially when working at the exceedingly high velocities called for in modern practice. With my invention the need for lubrication is lessened, while at the same time the matter of providing properly for effecting 90 lubrication is facilitated and less injury will be experienced in case the supply of lubricant should run low.

By way of enabling the lubrication of the contacting surfaces of the moving parts to be 95 effected conveniently and readily without loss of time or waste of lubricant I chamber the ring-rail, as shown in Figs. 1, 2, and 3,

and I arrange the antifriction rolls or wheels within the cavity or chamber of the rail. The lubricant is simply poured into the cavity or chamber. The lower ends of the pins 3^a 3^a 5 and portions of the antifriction rolls or wheels extend downward into the chamber or cavity of the rail to near the bottom of the said chamber or cavity, and consequently become more or less immersed in the lubricant, which thereby is enabled to work in between the bearing-surfaces of the said rolls or wheels and the pins and also is carried by the rotation of the rolls or wheels to the portion of the ring which engages with the latter. Thereby all relatively moving surfaces are lubricated. In this construction the V-shaped rib 2^b is formed on a skirt projecting downwardly below the band-groove of the ring, the said skirt and V-shaped rib also extending below the plates 3^b, on which the antifriction rolls or wheels are mounted. The ring is arranged concentrically with relation to a sleeve 4, rising from the bottom of the chamber or cavity of the ring-rail. The spindle in connection with which the ring is employed passes upward in practice through the opening of this sleeve. For the purpose of more effectually providing against access of the lubricant to the spindle and to the bobbin or cop-tube and yarn-load thereon I continue the said sleeve 4 upward above the general level of the top of the ring-rail, as shown most clearly in Fig. 1, and I chamber the ring interiorly, as at 2^c, to receive the upper portion of the sleeve. It is not intended that the sleeve and ring shall make lateral contact with each other. The chambering of the ring is advantageous in that it reduces the weight of the same.

55 are cover-plates which are applied to the top of the ring-rail above the plates 3^b 3^b. The inwardly-projecting portions of the plates 3^b 3^b are beveled off, as at 3^f 3^f, Fig. 1, in order that lubricant flashing off the antifriction-rolls or the rib 2^b of the ring and striking against the ends of such portions may be deflected downward instead of being caused to spatter upward against the cover-plates 55, the upper portion of the ring, or the driving-band.

50 For the purpose of enabling any required adjustment of the antifriction rolls or wheels relatively to the ring to be made—as, for example, for the purpose of causing the said rolls or wheels to fit properly against the ring as well as for the purpose of enabling the ring to be adjusted transversely into concentricity with the spindle—the plates 3^b 3^b are slotted, as described at 3^a 3^a, where the screws 3^c 3^c pass through the same into the lugs 1^a 1^a of the ring-rail. For convenience in enabling the required adjustment to be made I provide, in connection with the said plates 3^b 3^b, adjusting devices, here shown as constituted by set-screws 3^e 3^e, passing inwardly through tapped holes in the side walls of the ring-rail and making contact at their inner ends with

the outer edges of the plates 3^b 3^b, the said set-screws being provided with lock-nuts 3ⁱ 3ⁱ.

I provide the antifriction rolls or wheels 3 3 with elongated bearing portions 3^j 3^j, fitting 70 the pins 3^a 3^a, in order to distribute the wear, prevent unequal cutting or wearing of the said pins, and secure increased steadiness of the said rolls or wheels and the ring 2.

Various changes may be made in the form 75 and arrangement of the antifriction rolls or wheels 3 3 and the coöperating portion of the ring, as well as in the relations of these parts, without involving a departure from the principles of the invention. Thus the peripheries 80 of the rolls may be formed as short cylinders, as at 3^k in Fig. 5, entering right-angled grooves in the skirt of the ring, or the peripheries may be beveled, as at 3^l, Fig. 6, entering a corresponding inclined or beveled groove in 85 the skirt of the ring. Where the antifriction rolls or wheels are desired to hold the ring from upward movement without supporting the same vertically, the said rolls or wheels and ring may be shaped and combined as in 90 Figs. 7 and 8. Where the rolls or wheels are required to support the ring vertically without acting to prevent the same from rising, the parts may be shaped and combined as in Fig. 9.

95 The number of rolls or wheels employed in connection with each ring may be varied in practice.

The ring is provided in practice with a suitable guide 9, through which the roving or yarn 100 passes on its way to the spindle, bobbin, or other receiver.

What I claim is—

1. In a spinning or twisting machine, in combination, the chambered support, the rotating ring having the lower portion thereof received within the chamber of the said support, the plates fitting around the said portion of the ring from opposite sides thereof, and the antifriction rolls or wheels supported 105 by the said plates within the oil-containing space of the support.

2. In a spinning or twisting machine, in combination, the chambered support having the central sleeve extending upwardly within 115 the chamber thereof and the said chamber adapted to contain oil, the rotating ring surrounding the said sleeve and working within said chamber, and the antifriction rolls or wheels working within the said chamber and 120 engaging with the lower portion of the ring.

3. In a spinning or twisting machine, in combination, the chambered support having the central sleeve rising within the chamber thereof, the rotating ring surrounding the 125 said sleeve, the plates fitting around the said ring from opposite sides thereof, and the antifriction rolls or wheels supported by the said plates within the chamber.

4. In a spinning or twisting machine, in 130 combination, the chambered support, the chamber thereof being adapted to contain oil,

the rotating ring working within said chamber, and the antifriction rolls or wheels engaging with the said ring and working in the oil-containing chamber of the said support, substantially as described.

5. In a spinning or twisting machine, in combination, the chambered support, the chamber thereof being adapted to contain oil, the rotating ring having the depending skirt 10 entering the chamber of the said support, and the antifriction rolls or wheels engaging with the said skirt and working in the said chamber.

6. In a spinning or twisting machine, in combination, the rotating ring, the plates fitting around the lower portion of the ring from 15 opposite sides, and the antifriction rolls or wheels carried by the said plates and engaging with the lower portion of the said ring.

7. In a spinning or twisting machine, in combination, the chambered support, the chamber thereof being adapted to contain oil, the rotating ring, provided with a guide 20 through which the material being twisted or spun is led, with means for receiving applied force whereby to drive the same, and with a depending skirt working within the said chamber, and a series of antifriction rolls or wheels also working within said chamber and making contact only with the said skirt below 25 the place where driving power is applied to the ring.

8. In a spinning or twisting machine, in combination, the chambered support, the chamber thereof being adapted to contain oil, the rotating ring provided with a guide 35 through which the material being twisted or spun is led, with means for receiving applied force whereby to drive the same, and with a depending skirt shaped for engagement with the supporting rolls or wheels and working 40 within the said chamber, and a series of antifriction rolls or wheels also working within the said chamber and engaging with the said skirt only below the place where driving power is applied to the ring and acting to restrain the ring from vertical movement. 45

9. In a spinning or twisting machine, in combination, the chambered support, the rotating ring having the lower portion thereof received within the chamber of the said support, the plates fitting around the said portion of the ring from opposite sides thereof, the antifriction rolls or wheels supported by the said plates, and means to adjust the said plates. 50

In testimony whereof I affix my signature in presence of two witnesses.

JOHN MARSHALL.
